A. F. Bourne

UNITED STATES PATENT OFFICE.

RICHARD BRUSSEL, OF NEW YORK, N. Y.

CUFF.

1,297,538.

Specification of Letters Patent. Patented Mar. 18, 1919.

Application filed February 19, 1918. Serial No. 218,169.

To all whom it may concern:

Be it known that I, RICHARD BRUSSEL, a citizen of the United States, and resident of New York city, borough of Manhattan, in the county of New York and State of New York, have invented certain new and useful Improvements in Cuffs, of which the following is a specification.

Some shirts and shirtwaists are made with so-called "soft" or foldable cuffs, which are usually worn with the free portion folded outwardly over the part that is attached to the sleeve or wristband.

The object of my invention is to provide means to overlie or oppose the free edge portions of the cuffs when the latter are folded inwardly to prevent such folded portions of the cuffs from being engaged by the fingers of the user while the hands slide through the sleeves and cuffs when applying the shirt or shirtwaist to the person, and whereby the edge portions of the infolded cuffs will be kept out of contact with the wrists of the user.

In carrying out my invention I provide a shirt or shirtwaist having soft or foldable cuffs with a flap or web located along the inner side of the cuff at the wristband, providing a space to receive and conceal the free edge portions of the cuffs when the latter are folded inwardly. By the means described the cuffs may be used on one occasion with the free edge portion folded outwardly, in the ordinary manner, and on another occasion with the free edge portions of the cuffs folded inwardly and protected by the aforesaid flaps or webs.

My invention comprises novel details of improvement and combinations of parts that will be more fully hereinafter set forth and then pointed out in the claims.

Reference is to be had to the accompanying drawings forming part hereof, wherein,

Figure 1 is a perspective view illustrating a shirt or shirtwaist sleeve embodying my improvements, showing the cuff folded outwardly in an ordinary manner; Fig. 2 is a similar view showing the cuff folded inwardly in accordance with my invention; Fig. 3 is a diagrammatic view of the inside of a cuff, illustrating my improvements with the cuff unfolded; Fig. 4 is a similar view illustrating the cuff folded in accordance with my invention; Fig. 5 is a longitudinal section, on an exaggerated scale, substantially on the line 5, 5, in Fig. 3, and Fig. 6 is a view similar to Fig. 5 illustrating a modification.

Similar numerals of reference indicate corresponding parts in the several views.

At 1 is indicated a portion of the sleeve of a shirt or shirtwaist or other garment, and the cuff thereon is indicated generally at 2. Said cuff is of the "soft" or foldable variety attached at or near one edge portion to the sleeve, as at 3, by suitable stitching, which cuff is adapted to be folded, as along the fold line indicated at 4 in Fig. 3. The free portion 2^a of the cuff is adapted to be folded either outwardly in an ordinary manner or use as indicated in Fig. 1, or inwardly as indicated in Figs. 2 and 4. At 5 is indicated a flap or web located along the inner portion of the cuff adjacent to its attachment to the sleeve, to receive the inwardly folded portion 2^a of the cuff, which is adapted to be laid or folded between said flap and the main portion 2^b of the cuff. The flap 5 is suitably attached to the cuff or sleeve, or both, adjacent to the wristband portion of the sleeve, and said flap extends freely forwardly toward the outer end of the cuff to permit the foldable portion of the cuff to be concealed behind said flap. The cuff and flap may be made in any suitable manner, with or without a lining. In Fig. 5 the material of the cuff and of the flap are shown in a single piece having the inner webs 6 and 7 (which may provide the lining), and the outer webs 8 and 9, which provide the exposed or wearing portions of the cuff, the web portions 7 and 9 being continued freely beyond the stitching 3 and folded to form the flap 5. Instead of the webs 6, 7, being continuous with the webs 8, 9, the webs 6, 7, may be substituted by one or more ply of other material for a lining. In Fig. 6 the webs 6, 7, 8 and 9 are separate from the flap 5, the latter being shown made of folded material secured at its portion 5^a by the stitching 3 to the adjacent portion of the cuff and sleeve. Other details in the manufacture of the cuff and flap may be adopted as may be desired, the essential feature of my invention being the provision of the flap along the inner portion of the sleeve and cuff to overlie the foldable portion 2^a of the cuff when the latter is adjusted, as indicated in Figs. 2 and 4. The cuff links may be applied in the button holes 10, of the cuffs in an ordinary manner, in whichever position the cuff may be folded, since the flap 5 does not extend

so far outwardly as to interfere with the button holes, the edge portions 5^a of the flap being shown curved. The flap 5 is shown of less width than the width of the cuff when folded, and the outer curved corner edge portions 5^a of the flap recede from the outer edges of the cuff, spaced from the button holes 10, so as not to be observed when in use.

10 In accordance with my improvements the cuffs may be used with the portion 2^a folded outwardly in an ordinary manner, (Fig. 1), and, when desired, the cuff may be reversed by folding the portion 2^a inwardly and locating its free portion between the part 2^b of the cuff and the flap 5, as indicated in Figs. 2 and 5, whereby a clean portion of the cuff will be exposed. The flap 5, by extending from its attachment to the sleeve or 20 cuff, freely toward the outer end of the cuff, covers the free edge of the portion 2^a so that when the hand is pushed through the sleeve and cuff the flap 5 guides the fingers to prevent them from engaging with the inwardly folded portion 2^a of the cuff, and the 25 position of such folded portion is not disturbed. Furthermore, the flap 5, when overlying the folded portion 2^a of the cuff, retains the latter smoothly in position, and 30 protects it from contact with the flesh of the user.

While I have referred to my improvements as used in connection with foldable cuffs, upon sleeves of shirts or shirtwaists, 35 it will be understood that my invention is equally applicable to other portions of garments, such as upon so-called cuffs at the bottoms of legs of trousers.

Another advantage of my invention is 40 that since the cuff may be used at one time as shown in Fig. 1, and at another time as shown in Fig. 2, the wear on one side of the cuff may be reduced, since when the cuff is soiled it may be reversed, whereby one face 45 of the cuff may be subjected to approxi-

mately one-half of the wear ordinarily imposed upon cuffs that are not used folded.

While I have illustrated my improvements as secured by stitching to the sleeve, it will be obvious that the foldable cuff with 50 the flap 5 attached thereto may be made of the separable variety and attached to the wristband or sleeve, as by means of buttons and button holes or clips in the ordinary manner of attaching detachable cuffs to 55 sleeves.

Having now described my invention what I claim is:

1. The combination of a sleeve, a foldable cuff attached to the sleeve, and a flap secured within the sleeve and cuff and having a free portion extending toward the outer end of the cuff to receive therebetween the free portion of the cuff when the latter is folded inwardly, said cuff having button 60 holes located outwardly beyond the flap, the adjacent edges of the flaps being spaced from said button holes to not interfere with the latter, the mid portion of the flap being sufficiently wide to retain the folded portion 70 of the cuff when the latter is between the flap and the inner portion of the cuff.

2. The combination of a sleeve, with a cuff secured along one edge of the sleeve and adapted to be folded inwardly and outwardly beyond the sleeve, with a flap extending along the inner surface of the cuff and secured at its inner portion and free from the cuff at its outer portion to receive therebetween the outer edge portion of the 80 cuff when the latter is folded inwardly, said cuff having button holes, the outer corner edge portions of the flap receding from the outer edges of the cuff, said outer corners of the flap being spaced from said button 85 holes to not interfere with the latter.

Signed at New York city, in the county of New York and State of New York this 18th day of February A. D. 1918.

RICHARD BRUSSEL.
